THIADIAZOLE

Jan Hendrik Uhlenbroek and Johan Dirk Bijloo, Van Houtenlaan, Weesp, Netherlands, assignors to North American Philips Company, Inc., New York, N.Y., a corporation of Delaware
No Drawing. Filed Feb. 13, 1959, Ser. No. 792,953
Claims priority, application Netherlands Feb. 13, 1958
29 Claims. (Cl. 167—33)

It is known that 1,2,4-thiadiazoles, in which both carbon atoms of the ring carry monovalent organic radicals linked through sulphur, might be used for combating noxious insects and larvae of them. These organic radicals may be alkyl-, cycloalkyl-, aralkyl-, alkoxyalkyl-, aryloxyalkyl-, carbethoxyalkyl- or hydroxyalkyl groups.

It has now been found that 1,2,4-thiadiazoles, in which a halogen atom is linked to one of the carbon atoms of the ring are active against noxious organisms and in particular have a nematocide effect.

The present invention relates to a method of producing a means for combating noxious organisms and in particular nematodes, characterized in that a compound of the general formula:

in which Hlg represents a halogen atom and R₁ represents a phenyl group or a group R₂S—, in which R₂ represents a whether or not substituted, saturated or unsaturated, alkyl-, cycloalkyl-, aryl- or aralkyl group, the aliphatic chain whether or not being interrupted by oxygen or sulphur, is mixed with inert, solid or fluid carriers, if desired with the addition of surface-active materials and/or dispersion agents.

A satisfactory nematocide effect have, in particular, the compounds according to the invention, in which Hlg represents a chlorine atom and R₂ represents an alkyl group with 1 to 12 carbon atoms such as methyl-, ethyl-, propyl-, isopropyl-, butyl-, isobutyl-, isoamyl-, hexyl- or octyl group or an oxygen interrupted alkyl group such as an ethoxyethyl group or an unsaturated group, for example an allyl group and further compounds, in which R₂ represents a phenyl-, 4-chlorophenyl-, 4-methylphenyl group or a benzyl- or 4-chlorobenzyl group or a phenoxyethyl group.

Excellent nematocides are compounds according to the invention in which Hlg is a chlorine atom and R₁ represents a phenyl group, as well as those in which R₂ represents an unbranched alkyl group comprising 1 to 6 carbon atoms, an allyl group, an ethoxyethyl group or a phenyl-, 4-chlorophenyl or 4-methylphenyl group or a benzyl- or 4-chlorobenzyl group.

Particularly those nematodes are attacked by compounds according to the invention which cause eel worm diseases in plants, for example *Heterodera* species, for example larvae of *Heterodera rostochiensis* (potato cysticolar eel worm), *Meloidogyne* species (root knot eel worms) *Ditylenchus* species (stem eel worms), *Pratylenchus* species, *Hoplolaimus* species and larvae of *Anguina tritici* (wheat gall eel worms).

Tests showing the nematocide effect of compounds according to the invention were carried out as follows.

30 mgs. of the compound to be tested were finely ground with the addition of 5 drops of a solution of 5% of polyethylenemonolaurate and subsequently suspended in 30 ccs. of water. By diluting this suspension with water suspensions of different concentrations were obtained which were used for carrying out the tests.

1.5 ccs. of the suspension to be tested and subsequently

approximately 100 nematodes were introduced into an embryo tray of 4 by 4 cm. having a cavity of 3.5 ccs. Subsequently, the tray was closed by means of a roughly ground glass guard in such manner as to admit a quantity of oxygen sufficient to prevent immobilisation of the nematodes by lack of oxygen. By means of a binocular the vitality of the nematodes was determined after 4, 24, 48 and 140 hours respectively.

In this manner the lowest concentration of active compound in the suspension used was determined, which resulted in 100% kill of the test specimen after 140 hours exposure.

The tests were carried out on larvae of *Heterodera rostochiensis* lured for two days from their cysts, *Ditylenchus dipsaci* and larvae of *Anguina tritici* (both specimens soaked for 17 hours from dry condition).

The results of these tests are listed in Table I, which states the minimum lethal dosage of the investigated compound, killing all the test specimens within 140 hours' exposure. The minimum lethal dosage stated is the concentration of the active compound of the suspension used, expressed in parts by weight of active compound per million parts by weight of diluent (water).

25 TABLE I

R ₁ =	Compound	Nematodes

Table II states the results of a series of tests with 3-50 n.butylmercapto-5-chloro-1,2,4-thiadiazole in vitro, carried out as before. The table states the percentage of nematodes killed within 140 hours' exposition under the influence of the thiadiazole referred to.

55 TABLE II

Nematode	Concentration of active substance in parts per million						
	500	100	50	25	12	6	3
<i>Heterodera rostochiensis</i> (larvae)	100	100	100	100	100	100	90
<i>Ditylenchus dipsaci</i>	100	100	100	100	30	—	—
<i>Anguina tritici</i> (larvae)	100	100	100	100	100	60	—

65 The effect of three compounds on nematodes in the soil was investigated. The soil used was sandy, by its nature strongly infected with *Pratylenchus pratensis*. In separate tests, samples of 250 gms. of the soil were mixed with suspensions of 50, 25 and 10 mgms. respectively of the substance to be tested in 12 ccs. of water and subsequently stored for 24 days in cups at approximately 15° C. In order to prevent drying out of the

soil the cups were covered with a polythene foil. The nematodes were subsequently washed out of the soil in the manner referred to by J. W. Seinhorst and the survivors were counted (see *Nematologica*, vol. I, pages 249 to 267 (1956)). The same was done with blank-tests without adding active substance to the soil.

The tests were carried out five times.

Table III states the average result of these tests for each of the following compounds:

UE 9=3-phenyl-5-chloro-1,2,4-thiadiazole,
UE 18=3-methylmercapto-5-chloro-1,2,4-thiadiazole,
UE 19=3-n.butylmercapto-5-chloro-1,2,4-thiadiazole,
UE 32=3-n.propylmercapto-5-chloro-1,2,4-thiadiazole.

TABLE III

Compound	Mg. active substance per 250 g. of soil	Surviving nematodes	Kill percentage
UE 9	50	52	87

UE 32	25	32	96
	10	52	93
	5	50	93
	0	758	-----

Principally known methods may be used for producing the pesticidal preparations. Thus, for example, the active compounds according to the invention may be mixed with a pulverulent inert carrier, for example chalk, dolomite, attapulite, kaolin or pipe clay, or dissolved or dispersed in an inert solvent such as toluene, xylene, aliphatic or aromatic ketones, for example acetone, methyl-ethyl-ketone or cyclohexanone, or mixtures of them with said hydrocarbons, if desired with the addition of surface-active materials and/or dispersion agents. As an alternative, these preparations may be mixed with synthetic fertilisers.

For example, a dust is prepared by grinding approximately 5 parts by weight of an active compound according to the invention together with approximately 95 parts by weight of kieselguhr to an average particle size of approximately 10μ .

For example a wettable powder is produced by mixing approximately 50 parts by weight of an active compound according to the invention with approximately 5 parts by weight of oleylamido-methyltaurate, approximately 10 parts by weight of calciumligninsulfonate and approximately 35 parts by weight of dolomite (calcium-magnesium carbonate), this mixture being ground to an average particle size of approximately 10μ .

Miscible oils may, for example, be produced by dissolving approximately 25 parts by weight of an active compound according to the invention in a mixture of approximately 10 parts by weight of an active compound according to the invention in a mixture of approximately 10 parts by weight of polyoxyethylenesorbitan fatty acid ester, approximately 10 parts by weight of methylethyl-ketone and approximately 55 parts by weight of xylene.

The compounds according to the invention permit in general, miscible oils of high concentration to be produced. Thus, for example, 3-n.butylmercapto-5-chloro-1,2,4-thiadiazole with xylene can be worked up to a miscible oil containing 80 percent by weight of active material. This may be of importance in practice.

The production of a number of the compounds according to the invention has already been described. (See J. 75

Goerdeler et al., *Chem. Berichte* 90, 182 et seq. and 892 et seq. (1957).) An amidin salt of isothiouronium salt in water in reacted with an equivalent quantity of perchloromethylmercaptan with the addition of soda lye.

Several of the compounds according to the invention, in which R_1 represents the group R_2S have, however, not yet been mentioned in the literature. These compounds can be produced by the aforesaid method from isothiouronium salts and perchloromethylmercaptan. Novel 10 compounds are inter alia those in which in the aforesaid formula R_2 represents one of the following groups: isopropyl, 1-methylpropyl, 3-methylpropyl, n.amyl, n.hexyl, n.octyl, n.dodecyl, allyl, ethoxyethyl, phenyl, 4-chlorophenyl, 4-methylphenyl and phenoxyethyl.

15 The production of a number of these novel compounds will be described in Examples I to V.

Example I

3-PHENYLMERCAPTO-5-CHLORO-1,2,4-THIADIAZOLE

In a 3 litre flask, 188.5 gms. (1.0 mole) of phenylisothiouroniumchloride were mixed with 186 gms. (1.0 mole) of perchloromethylmercaptan, 180 ccs. of water and 300 ccs. of methylenechloride, while cooling the flask with ice-water. Subsequently, a solution of 160 gms. (4.0 mole) of sodium-hydroxide in 500 ccs. of water was slowly added to the mixture, while stirring vigorously. 35 The rate of adding the soda lye was such that the temperature did not exceed 5° C. and the mixture did not produce an alkaline reaction. After adding the whole quantity, stirring was continued for half an hour. Subsequently 25 ccs. of ammonia (25% by weight) were added and further stirred for 15 minutes, followed by neutralisation with hydrochloric acid.

40 The layer of methylene chloride, in which the reaction product is dissolved, was separated, washed with 0.5 l. of water and dried on anhydrous sodium sulphate. After distilling off the methylene chloride the residue, that is the crude reaction product, was crystallised from petroleum ether (boiling range 40° C. to 60° C.). Yield 148 gms. of 3-phenylmercapto-5-chloro-1,2,4-thiadiazole (yield 65%). Melting point 58° C.

45 The compounds used in the Examples II to V were produced quite similarly.

Example II

3-n.OCTYLMERCAPTO-5-CHLORO-1,2,4-THIADIAZOLE

55 22.4 gms. (yield 68%) of 3-n.octylmercapto-5-chloro-1,2,4-thiadiazole were obtained from 33.6 gms. (0.125 mole) of n.octylisothiouronium bromide and 23.3 gms. (0.125 mole) of perchloromethylmercaptan. Boiling point: 145° to 146° C. at 8 mms. mercury pressure.

60

65 22.2 gms. (yield 46%) of 3-allylmercapto-5-chloro-1,2,4-thiadiazole were produced from 49.3 gms. (0.25 mole) of allylisothiouronium bromide and 46.5 gms. (0.25 mole) of perchloromethylmercaptan. Boiling point 115-117° C. at 15 mms. mercury pressure.

Example III

3-(4'-CHLOROBENZYL)MERCAPTO-5-CHLORO-1,2,4-THIADIAZOLE

70 17 gms. (yield 46%) of 3-(4'-chlorobenzyl)mercapto-5-chloro-1,2,4-thiadiazole were produced from 32 gms. (0.13 mole) of 4-chlorobenzylisothiouronium chloride and 25 gms. (0.13 mole) of perchloromethylmercaptan.

After crystallisation from ligroin the melting point was 52° C.

Example V

3-(4'-NITROBENZYL)MERCAPTO-5-CHLORO-1,2,4-THIADIAZOLE

14.5 gms. (yield 59%) of 3-(4'-nitrobenzyl)mercapto-5-chloro-1,2,4-thiadiazole were obtained from 25 gms. (0.086 mole) of 4-nitrobenzylsophiuronium bromide and 16 gms. (0.086 mole) of perchloromethylmercaptan. After crystallization from a mixture of benzene and ligroin (1:1) the melting point was 97° C.

In Table IV are listed the yields obtained by the production method described in the aforesaid examples and physical constants of several novel 5-chloro-1,2,4-thiadiazoles according to the invention.

TABLE IV

$\text{R}_2-\text{S}-\text{C}(=\text{N})-\text{C}(=\text{S})-\text{Cl}$	Melting point, °C.	Boiling point °C. at mm. mercury pressure	Yield, percent
$\text{R}_2=$			
Isopropyl		110° to 112° at 14 mm.	20
$(\text{CH}_3)_2\text{CH}_2\text{CH}-\text{CH}_3$		128° to 128° at 14 mm.	25
$(\text{CH}_3)_2\text{CH}-\text{CH}_2$		128° to 124° at 14 mm.	20
n-Amyl		102° to 104° at 0.7 mm.	60
n-Hexyl		110° to 112° at 0.02 mm.	46
n-Octyl		145° to 146° at 0.8 mm.	68
n-Dodecyl		180° to 183° at 0.05 mm.	60

4-nitrobenzyl	97		59

It was moreover found that the compounds according to the invention can be produced from the corresponding 5-amino-1,2,4-thiadiazoles according to the reaction of Sandmeyer, in which the amino compounds are converted into diazonium compounds by means of nitrite, for example sodium nitrite, which diazonium compounds are converted into 5-chloro-1,2,4-thiadiazoles in the presence of copper powder and a chloride, or in the presence of, for example, cuprous chloride.

This method will be set out in the following examples.

Example VI

3-BENZYLMERCAPTO-5-CHLORO-1,2,4-THIADIAZOLE

9.5 gms. (0.043 mole) of 3-benzylmercapto-5-amino-1,2,4-thiadiazole were dissolved in 100 ccs. of acetic acid. Whilst cooling with ice a solution of 4.9 gms. (0.07 mole) of sodium nitrite in 50 ccs. of concentrated hydrochloric acid was added dropwise such that the temperature of the mixture did not exceed 20° C. After standing 15 minutes at room temperature, the reaction mixture was poured out while stirring, in a solution of 6 gms. of cuprous chloride in 100 ccs. of concentrated hydrochloric acid. After standing overnight, the mixture obtained was shaken with benzene at room temperature. After concentration by evaporation, the benzene solution yielded 5.9 gms. (60%) of crude 3-benzylmercapto-5-chloro-1,2,4-thiadiazole from which the pure compound was obtained by crystallization from methanol. Melting point 49° C.

EXAMPLE VII

3-PHENYL-5-CHLORO-1,2,4-THIADIAZOLE

This compound was produced in a manner similar to that used in Example VI.

10.6 gms. (0.06 mole) of 3-phenyl-5-amino-1,2,4-thiadiazole were dissolved in 130 ccs. of acetic acid, followed by adding, while stirring, a solution of 4.56 gms. (0.066 mole) of sodium nitrite in 45 ccs. of concentrated sulfuric acid. The temperature was kept between 5° C. and 10° C. Subsequently, the temperature of the mixture was raised to 18° C. and the mixture was poured

out in a solution of 12 gms. (0.120 mole) of cuprous chloride in 120 ccs. of concentrated hydrochloric acid. The 3-phenyl-5-chloro-1,2,4-thiadiazole was extracted with petroleum ether (boiling range 40° C. to 60° C.) from the reaction mixture. Yield 6.85 gms. (58%).

Melting point 42° C. to 50° C.

What is claimed is:

1. A composition for the control of nematode comprising as an active ingredient a thiadiazole compound corresponding to the general formula:

15 wherein Hal represents a halogen atom and R_1 represents a radical selected from the group consisting of phenyl and the radical R_2S wherein R_2 represents a radical selected from the group consisting of alkyl, alkoxy-alkyl, allyl, phenyl, methylphenyl, chlorophenyl, benzyl, chlorobenzyl and phenoxyethyl in a nematocidal effective amount, a surface active material and a nematocide adjvant as a carrier therefor.

2. The composition of claim 1 wherein Hal represents a chlorine atom.

3. The composition of claim 1 wherein R_2 represents an alkyl radical containing 1 to 12 carbon atoms.

4. The composition of claim 1 wherein R_2 represents the ethoxyethyl radical.

5. The composition of claim 1 wherein R_2 represents an unbranched alkyl radical containing from 1 to 6 carbon atoms.

30 6. A dust for combating nematodes comprising an intimate mixture of about 5 parts by weight of the active compound of claim 1 and about 95 parts by weight of kieselguhr, said dust having an average particle size of approximately 10μ .

7. A wettable powder for combating nematodes comprising an intimate mixture of about 50 parts by weight of the active compound of claim 1, about 5 parts by weight of oleylamidomethylaurate, about 10 parts by weight of calcium ligninsulfonate and about 35 parts by weight of dolomite, said powder having an average particle size of about 10μ .

40 8. A miscible oil for combating nematodes comprising a solution of about 25 parts by weight of the active compound of claim 1 in a mixture of about 55 parts by weight of xylene, of about 10 parts by weight of methyl-ethyl-ketone and of about 10 parts by weight of polyoxyethylene-sorbitan fatty acid ester.

50 9. A composition for the control of nematodes comprising as an active ingredient 3-phenyl-5-chloro-1,2,4-thiadiazole in a nematocidal effective amount, a surface active material and a nematocide adjvant therefor.

10. A composition for the control of nematodes comprising as an active ingredient 3-alkylmercapto-5-chloro-1,2,4-thiadiazole in a nematocidal effective amount, a surface active material and a nematocide adjvant therefor.

60 11. A composition for the control of nematodes comprising as an active ingredient 3-ethoxyethylmercapto-5-chloro-1,2,4-thiadiazole in a nematocidal effective amount, a surface active material and a nematocide adjvant therefor.

12. A composition for the control of nematodes comprising as an active ingredient 3-phenylmercapto-5-chloro-1,2,4-thiadiazole in a nematocidal effective amount, a surface active material and a nematocide adjvant therefor.

70 13. A composition for the control of nematodes comprising as an active ingredient 3-n-butylmercapto-5-chloro-1,2,4-thiadiazole in a nematocidal effective amount, a surface active material and a nematocide adjvant therefor.

14. A composition for the control of nematodes comprising as an active ingredient 3-methylmercapto-5-chloro-

ro-1,2,4-thiadiazole in a nematocidal effective amount, a surface active material and a nematocide adjuvant therefor.

15. A composition for the control of nematodes comprising as an active ingredient 3-(4¹-chlorophenyl)-mercapto-5-chloro-1,2,4-thiadiazole in a nematocidal effective amount, a surface active material and a nematocide adjuvant therefor.

16. A composition for the control of nematodes comprising as an active ingredient 3-(4¹-methylphenyl)-mercapto-5-chloro-1,2,4-thiadiazole in a nematocidal effective amount, a surface active material and a nematocide adjuvant therefor.

17. A composition for the control of nematodes comprising as an active ingredient 3-benzylmercapto-5-chloro-1,2,4-thiadiazole in a nematocidal effective amount, a surface active material and a nematocide adjuvant therefor.

18. A composition for the control of nematodes comprising as an active ingredient 3-(4¹-benzylmercapto)-5-chloro-1,2,4-thiadiazole in a nematocidal effective amount, a surface active material and a nematocide adjuvant therefor.

19. A method of combating nematodes comprising treating the habitat thereof with the composition of claim 1.

20. A method of combating nematodes comprising treating the habitat thereof with the composition of claim 9.

21. A method of combating nematodes comprising 30 treating the habitat thereof with the composition of claim 10.

22. A method of combating nematodes comprising treating the habitat thereof with the composition of claim 11.

10

15

20

25

30

35

23. A method of combating nematodes comprising treating the habitat thereof with the composition of claim 12.

24. A method of combating nematodes comprising 5 treating the habitat thereof with the composition of claim 13.

25. A method of combating nematodes comprising treating the habitat thereof with the composition of claim 14.

26. A method of combating nematodes comprising treating the habitat thereof with the composition of claim 15.

27. A method of combating nematodes comprising treating the habitat thereof with the composition of claim 16.

28. A method of combating nematodes comprising treating the habitat thereof with the composition of claim 17.

29. A method of combating nematodes comprising 20 treating the habitat thereof with the composition of claim 18.
